PICKUP FOR ADAPTING GRAND PIANO FOR ELECTRIC AMPLIFICATION

Charles T. Helpinstill II, 6124 Tessamine,
Houston, Tex. 77036

Filed July 8, 1974, Ser. No. 486,491

Term of patent 14 years

Int. Cl. D17—99

U.S. Cl. D56—1 R

FIG. 1

FIG. 1 is a perspective view of a pickup for adapting a grand piano for electric amplification showing my new design;

FIG. 2 is an elevational view;

FIG. 3 is a top plan view; and

FIG. 4 is a partial sectional view taken along line 4—4 of FIG. 3.

I claim:

The ornamental design for a pickup for adapting grand piano for electric amplification, substantially as shown and described.
